(57) CLAIM

The ornamental design for a playpen, as shown and described.

DESCRIPTION

FIG. 1 is a top perspective view of a playpen showing my new design;

FIG. 2 is a front view thereof, a rear view being a mirror image of the front view;

FIG. 3 is a left side view thereof, a right side view being a mirror image of the left side view;

FIG. 4 is a top view thereof;

FIG. 5 is a bottom view thereof;

FIG. 6 is a bottom perspective view thereof;

FIG. 7 is a partially enlarged view showing the area 7 in FIG. 1;

FIG. 8 is a partially enlarged view showing the area 8 in FIG. 1;

FIG. 9 is a partially enlarged view showing the area 9 in FIG. 1;

FIG. 10 is a partially enlarged view showing the area 10 in FIG. 1;

FIG. 11 is a partially enlarged view showing the area 11 in FIG. 1;

FIG. 12 is a partially enlarged view showing the area 12 in FIG. 1;

FIG. 13 is a partially enlarged view showing the area 13 in FIG. 1;

FIG. 14 is a partially enlarged view showing the area 14 in FIG. 1;

FIG. 15 is a partially enlarged view showing the area 15 in FIG. 1;

FIG. 16 is a partially enlarged view showing the area 16 in FIG. 1;

FIG. 17 is a partially enlarged view showing the area 17 in FIG. 1;

FIG. 18 is a partially enlarged view showing the area 18 in FIG. 1;

FIG. 19 is a partially enlarged view showing the area 19 in FIG. 1; and,

FIG. 20 is a partially enlarged view showing the area 20 in FIG. 1.

The dot-dash broken lines indicating an enlargement portion of the design form no part of the claimed design.
The broken lines depict portions of the playpen that form no part of the claimed design.

1 Claim, 15 Drawing Sheets
